BAR CABINET

Michele Renna, Los Angeles, Calif.

Application March 31, 1951, Serial No. 14,680

Term of patent 14 years

(Cl. D33—19)

To all whom it may concern:

Be it known that I, Michele Renna, a citizen of the United States, residing at Los Angeles, county of Los Angeles, State of California, have invented a new, original, and ornamental Design for a Bar Cabinet, of which the following is a specification, reference being had to the accompanying drawing, forming part thereof:

Fig. 1 is a front elevational view of a bar cabinet showing my new design;

Fig. 2 is a perspective view thereof with the auxiliary door shown in open position;

Fig. 3 is a perspective view taken from the opposite side and showing the interior portion revolved 180°; and

Fig. 4 is a plan view with the revolvable structure rotated 90° from closed position.

I claim:

The ornamental design for a bar cabinet, as shown.

MICHELE RENNA.
